(57) **CLAIM**

The ornamental design for a framing square combination tool, as shown and described.

DESCRIPTION

FIG. 1 is an isometric view of the framing square combination tool;

FIG. 2 is another isometric view thereof;

FIG. 3 is a left side thereof;

FIG. 4 is a front side thereof;

FIG. 5 is a right side thereof;

FIG. 6 is a rear side thereof;

FIG. 7 is a top view thereof;

FIG. 8 is a bottom view thereof;

FIG. 9 is an isometric view thereof in which a t-bevel element thereof is in an alternate position;

FIG. 10 is an elevation view of the rear side thereof in which a lip element thereof is shown in a first alternate position;

FIG. 11 is an elevation view of the rear side thereof in which the lip element thereof is shown in a second alternate position;

FIG. 12 is an isometric view of another embodiment of the framing square combination tool;

FIG. 13 is another isometric view thereof;

FIG. 14 is a left side thereof;

FIG. 15 is a front side thereof;

FIG. 16 is a right side thereof;

FIG. 17 is a rear side thereof;

FIG. 18 is a top view thereof;

FIG. 19 is a bottom view thereof;

FIG. 20 is an isometric view thereof in which a t-bevel element thereof is in an alternate position;

FIG. 21 is an elevation view of the rear side thereof in which a lip element thereof is shown in a first alternate position;

FIG. 22 is an elevation view of the rear side thereof in which the lip element thereof is shown in a second alternate position;

FIG. 23 is a left side of another embodiment of the framing square combination tool;

FIG. 24 is a front side thereof;

FIG. 25 is a right side thereof;

FIG. 26 is a rear side thereof;

FIG. 27 is a top view thereof;

FIG. 28 is a bottom view thereof;

FIG. 29 is a front view thereof in which a t-bevel element thereof is in an alternate position;

FIG. 30 is an elevation view of the rear side thereof in which a lip element thereof is shown in a first alternate position; and,

FIG. 31 is an elevation view of the rear side thereof in which the lip element thereof is shown in a second alternate position.
